REVERSIBLE MOP

Felix K. Bogan, Milford, Conn.

Application May 24, 1950, Serial No. 163,997

6 Claims. (Cl. 15—119)

1

This invention relates to a mop of the type which is employed in washing floors, walls, and windows and which is provided with a resilient pad of durable absorbent material such as sponge rubber or sponge cellulose.

One object of this invention is to provide a mop of the above nature in which the pad is clamped between reinforcing plates in such a manner that two opposite edge portions of the pad will be available for selective use at all times.

Another object is to provide a mop of the above nature having improved means for releasably attaching a handle to the clamping plates.

Another object is to provide a mop of the above nature wherein the handle is provided with a swivel connection so constructed as to facilitate the operation of the mop in corners and other places which are difficult of access.

A further object is to provide a mop of the above nature which will be simple in construction, inexpensive to manufacture, easy to use and manipulate, compact, easy to replace, ornamental in appearance, and very efficient and durable in use.

With these and other objects in view, there have been illustrated on the accompanying drawings two forms in which the invention may be conveniently embodied in practice.

In the drawings,

Fig. 1 is a perspective view showing one form of the improved mop, the handle being omitted to show the construction of the swivel connection, and also showing a pair of wringer plates attached to the mop.

Fig. 2 is an end view of the same, partly broken away, and showing the handle assembled therewith.

Fig. 3 is a cross-sectional view of a portion of the same, taken on the line 3—3 of Fig. 1.

Fig. 4 is a perspective view showing the second form of the mop, the handle being broken away.

Fig. 5 is an end view of the same partly in section.

Fig. 6 is a cross-sectional view of a portion of the same, taken on the line 6—6 of Fig. 4.

Fig. 7 is a perspective view on a reduced scale, showing the mop as it would appear in use for cleaning a floor.

Referring now to the drawings, in which like reference numerals denote corresponding parts throughout the several views, the numeral 10 indicates the first form of the improved mop, which comprises a rectangular pad 11 of resilient porous material such as sponge rubber

clamped between back and front channel plates 12 and 13.

The channel plates 12, 13 are considerably narrower and shorter than the pad 11, so that a central portion of said pad will be compressed between said plates and opposite uncompressed edge portions 14, 15 of the pad will bulge outwardly above and below the plates 12, 13 and will be available for cleaning purposes.

Further, the portions of the pad 11 which extend beyond the ends of the plates 12, 13 will cushion the ends of said plates and thus prevent them from coming into contact with woodwork, furniture, or other objects which might otherwise be damaged.

The channel plates 12, 13 comprise pairs of outwardly inclined opposite edge flanges 16 which serve to reinforce the edge portions 14, 15 of the pad. The channel plates 12, 13 are clamped against opposite faces of the pad 11 by a pair of tongues 17, 18 which are struck inwardly from central portions of the back plate 12 and which pass forwardly through the pad 11 and through apertures in the plate 13, the front ends of said tongues being bent to engage the outer surface of said front plate.

In order to connect a handle 19 to the back channel plate 12, provision is made of a yoke member 20 comprising a base plate 21 which is shorter than said back channel plate, and which has a similar cross-sectional shape so that it may be clamped snugly against the rear surface of said back channel plate. One end of the base plate 21 is adapted to be engaged under an offset lug 22 struck outwardly from a central portion of the back channel plate 12, and the opposite end of said base plate 21 is formed with a longitudinal slot 23 adapted to receive the end of a screw 24 engaged through the pad 11 and the back and front plates 12, 13, a wing nut 25 being applied to said screw 24 for retaining the base plate 21.

It will be observed that the slot 23 has a length sufficient to permit the base plate 21 to be slid out of engagement with the offset lug 22 without removing the wing nut 25 completely from the screw 24, thus facilitating attachment and detachment of the base plate 21 with respect to the back channel plate 12.

The yoke member 20 also comprises a pair of inclined arms 26 which are bent inwardly from opposite edges of the base plate 21, the outer ends of said arms being bent to form substantially semi-circular parallel complementary

socket portions 27. The lower end of the handle 19 comprises a forty-five degree elbow 28 (Fig. 2), the forward end portion of which is formed with a peripheral bead 29 adapted to engage within a corresponding outwardly struck bead 30 in the socket portions 27, thus providing a swivel connection between the handle 19 and the absorbent pad 11. However, in order to prevent accidental separation of the elbow 28 from the socket portions 27, said socket portions are provided with opposed pairs of ears 31 which are held by nuts 32 and screws 33 engaged therethrough.

As a means for squeezing water from the pad 11, provision is made of one or more detachable wringer plates 34, each of which is preferably somewhat shorter than the back channel plate 12 and may be of approximately the same width as each of the projecting pad portions 14, 15. Each wringer plate 34 is preferably bent at a small angle in a transverse direction, and is provided at one edge thereof with a pair of hooks 35 adapted to be detachably engaged in pairs of apertures 36 adjacent the edges of the flanges 16 of the back channel plate 12.

It will be understood that the hooks 35 are adapted to connect the wringer plates 34 swingably to the channel plate 12 so that said wringer plates may be manually depressed for squeezing water from the edge portions of the pad 11.

Second form

The second form of the invention is embodied in a mop 37 comprising a rectangular pad 38 clamped between back and front channel plates 39, 40 in substantially the same arrangement as was described above in connection with the first form of the invention.

Thus, the pad 38 comprises relatively free un-compressed edge portions 41, 42 which are located outwardly of inclined edge flanges 43 of the channel plates 39, 40. It will be noted, however, that in the second form of the invention the channel plates 39, 40 are clamped together by means of a pair of C-shaped clamping elements 44 of stiff wire, which embrace the end edges of the pad 38 and the channel plates 39, 40, and which are retained by engagement of their ends in apertures in said channel plates (Fig. 6).

In order to connect a handle 45 to the back channel plate 39, provision is made of a yoke member 46 comprising a base plate 47 which is adapted to engage snugly against the rear surface of said back channel plate. The base plate 47 is similar to the base plate 21 described in connection with the first form of the invention, and is adapted to be held at one end by an outwardly offset lug 48 on the back channel plate 39, and at the other end by a screw 49, the latter being engaged through the pad 38, and the channel plates 39, 40, and being provided with a wing nut 50. The base plate 47 has an end slot 51 adapted to embrace the screw 49, as in the first form of the invention.

The handle 45 comprises a 45° elbow 52, the forward end portion of which is provided with a peripheral bead 53 adapted to seat upon an in-turned flange 54 formed at a central location in an apertured socket member 55. Opposite edge portions 55a of the socket member 55 are turned inwardly at a suitable inclination to engage opposite edge portions of the base plate 47, to which they are secured by suitable means such as welding or riveting.

In order to confine the peripheral bead 53 loosely against the in-turned flange 54, provision is made of a centrally apertured retaining ring 56 having an outturned flange 57 for engaging said bead, said ring being detachably secured to the socket member 55 by a plurality of screws 58.

Opposite edge portions of the upper channel plate 39 are formed with pairs of apertures 59 in order to permit the detachable connection of the wringer plates 34 thereto, as hereinbefore described.

Operation

In use, both forms of the mop will be operated in substantially the same way and may be used in connection with any suitable cleaning liquid for washing floors, windows, walls, or other objects. If, for example, the mop 10 is to be used for washing a floor, said mop will be so held that either the edge portion 14 or the edge portion 15 of the pad 11 will engage the floor, the other of said edge portions facing upwardly.

The lower end portion of the elbow 28 will, of course, be located in a horizontal position and the handle 19 will be disposed at a 45° inclination which will be convenient for manipulating the mop.

When it is desired to operate the mop in a corner or other place which may be difficult of access, the swivel connection at the lower end of the handle will permit the pad to be swung in a horizontal direction merely by rotating the handle 19.

When the user wishes to squeeze the water from the mop pad, it will merely be necessary to place the edge portion 14 of the pad 11 upon the edge of a sink or other suitable receptacle and depress the wringer plates 34. This operation may be repeated for squeezing the water from the edge portion 15. If desired, the wringer plates 34 may be removed during operation of the mop, and connected thereto only for the wringing operation.

Inasmuch as the edge portions 14, 15 of the pad 11 are selectively useable merely by inverting the head of the mop with respect to the handle 19, it will be seen that frequent washing or cleaning of the mop during use will be unnecessary, and the life of the pad 11 will be prolonged.

When the handle 19 is to be detached from the mop 10, it will merely be necessary to loosen the wing nut 25 sufficiently to permit the base plate 21 to be slid out of engagement with the offset lug 22, thus permitting said base plate to be disengaged from the nut 25. If desired, the mop pad, when disengaged from the handle, may be used manually for cleaning in narrow and inaccessible locations.

The second form of mop 37 will be operated in substantially the same manner as the mop 10, and a detailed description of its operation will, therefore, be unnecessary.

While there have been disclosed in this specification, two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what

is claimed as new and for which it is desired to secure Letters Patent, is:

1. In a mop, a pad clamped between a pair of parallel front and back plates and projecting beyond opposite edges of said plates, a yoke member comprising a base plate, a handle connected to said yoke member, means detachably securing said base plate against a central portion of said back plate, comprising a lug on said back plate overlapping one end of said base plate, and a 10 screw provided with a nut for clamping the other end of said base plate against said back plate, said base plate having an end slot embracing said screw and having an extent sufficient to permit said base plate to be released from said lug by movement in a longitudinal direction.

2. The invention as defined in claim 1, in which said handle comprises an elbow, and including means providing a swivel connection between said yoke member and said elbow, whereby an edge 20 portion of said pad may be swung horizontally with respect to said handle while remaining in full engagement with the floor.

3. The invention as defined in claim 1, in combination with a wringer plate integrally provided 25

with a pair of hooks at one edge thereof, said hooks being engageable with a pair of apertures adjacent the longitudinal edge of said back plate, whereby said wringer plate may be swung for compressing an edge portion of said pad.

5. The invention as defined in claim 1, in which an end portion of said handle is formed with a peripheral bead, said yoke member comprising a socket having means for confining said bead.

15. The invention as defined in claim 1, in which an end portion of said handle is formed with a peripheral bead, said yoke member comprising a socket having means for confining said bead.

5. The invention as defined in claim 1, in which an end portion of said handle is formed with a peripheral bead, said yoke member comprising a socket having means for confining said bead.
